[57] CLAIM

The ornamental design for an electrical adapter plug, as shown and described.

DESCRIPTION

FIG. 1 is a perspective view of a first embodiment of my electrical adapter plug showing my new design; FIG. 2 is a side elevation view of the electrical adapter plug;

FIG. 3 is an opposite side elevation view of the electrical adapter plug;

FIG. 4 is a rear elevation view of the electrical adapter plug;

FIG. 5 is a front elevation view of the electrical adapter plug;

FIG. 6 is a top view of the electrical adapter plug;

FIG. 7 is a bottom view of the electrical adapter plug; FIG. 8 is a perspective view of a second embodiment of my electrical adapter plug showing a modification of my new design;

FIG. 9 is a side elevation view of the second embodiment of the electrical adapter plug;

FIG. 10 is an opposite side elevation view of the second embodiment of the electrical adapter plug;

FIG. 11 is a rear elevation view of the second embodiment of the electrical adapter plug;

FIG. 12 is a front elevation view of the second embodiment of the electrical adapter plug;

FIG. 13 is a top view of the second embodiment of the electrical adapter plug; and,

FIG. 14 is a bottom view of the second embodiment of the electrical adapter plug.
